UNITED STATES PATENT OFFICE.

LUCIEN BUCK, OF NORTH ADAMS, MASSACHUSETTS, ASSIGNOR TO JAMES HUNTER MACHINE COMPANY, OF NORTH ADAMS, MASSACHUSETTS, A CORPORATION OF MASSACHUSETTS.

APPARATUS FOR STRETCHING AND DRYING WEBLIKE MATERIALS.

Application filed March 17, 1928. Serial No. 262,390.

This invention pertains to drying apparatus and more particularly to means for stretching and drying web-like materials such for example as textile fabric. It has 5 heretofore been common to equip automatic tenter frames, used for stretching lightweight woven goods, for instance cottons and silks) with direct radiation coils beneath the fabric (either with or without air circulation) 10 or to heat air at a point outside of the tentering frame and to deliver such heated air against one or both surfaces of the fabric by means of suitable distributing nozzles. Since the range in width of such woven materials is usually not very large (at least in 15 the same establishment) no special difficulty is encountered in drying the various widths on the same frame.

However, when dealing with knitted goods, 20 such as glove silks, rayon fabrics, etc. great variations in width are met with, for example, widths varying from thirty-six inches to one hundred and sixty inches, and it has been found practically impossible, by the 25 use of previously known apparatus, to dry all of such widths properly upon the same frame. Even though tentering frames have been made adjustable throughout the necessary range, no provision has been made for 30 a corresponding change in distribution of the drying medium and while the narrow widths may be dried properly, the marginal portions and selvages of the wider widths are 35 improperly dried so that when released from the frame the fabric curls and draws at its edges. For this reason it has been common to provide a series of tentering frames of graduated widths or to employ hand frames for drying and finishing knitted materials 40 of the class referred to.

In accordance with the present invention I am able to stretch and dry fabrics varying in width from thirty-six inches to one hundred and sixty inches,—for example, employing 45 a single tentering frame for the purpose and obtain substantially uniform and perfect results at all widths, the extreme selvages being thoroughly stretched and dried as well as the mid-portions of the material. In accomplishing this result I provide drying 50 means which automatically accommodates

itself to all variations in width of the frame and which furnishes the requisite drying effects at the marginal portions and selvages of the fabric, no matter what its width, while at 55 the same time thoroughly drying the central part of the fabric. While I have herein chosen to illustrate the invention as embodied in that type of machine in which the air is heated outside of the tenter frame proper 60 and discharged into contact with the fabric through a suitable delivery nozzle, I contemplate that as to its broadest principle at least it may be applied to other systems of drying, and I regard all such applications as falling 65 within the scope of the invention.

In the accompanying drawings I have illustrated by way of example one desirable embodiment of my invention but showing only such parts of the tentering frame proper 70 as are necessary to indicate the relation of the present invention thereto.

In the drawings,

Fig. 1 is a plan view of more or less diagrammatic character showing my improved 75 drying and stretching apparatus in its entirety;

Fig. 2 is a vertical section substantially on the line 2—2 of Fig. 1;

Fig. 3 is a fragmentary plan view showing 80 a desirable arrangement of drying means and indicating parts of the tentering frame proper in broken lines;

Fig. 4 is a vertical section on the line 4—4 of Fig. 3 showing portions of the tenter 85 frame in vertical section;

Fig. 5 is a fragmentary vertical section to larger scale, substantially on the line 5—5 of Fig. 3, and showing the parts in position for drying fabric of the widest width which the 90 machine is designed to accommodate;

Fig. 6 is a view similar to Fig. 5 but showing the parts arranged to dry a narrower fabric;

Fig. 7 is a diagrammatic plan view showing 95 a preferred arrangement of the nozzles; and

Figs. 8 to 14 inclusive are diagrammatic views illustrating certain illustrative modifications.

Referring to the drawings, the numeral 1 100 indicates generally my improved stretching

and drying apparatus. That portion, at least, of the apparatus at which the drying action takes place, is preferably housed within a room or enclosure R having walls 2. 5 These walls may be of any suitable material, preferably of a heat insulating character, and are provided with the necessary doors and air ingress and egress openings. I provide a fan blower 3 of any desired type, preferably 10 disposed outside of the room R and driven by means of a motor or from other source of power. The intake of this blower is connected to a casing 4 containing heating coils, such casing having a port 5 controlled by any 15 suitable form of damper and adapted to permit entrance of fresh up-keep air. The casing 4 is preferably also provided with an air inlet 6 communicating with a conduit 7 which extends into the room R and which is provided 20 with a damper-controlled opening or openings for receiving the warm air from the room R so that such air may be delivered to the casing 4 and the fan for recirculation.

The air from the fan 3 is delivered into a 25 passage 9 which leads to a conduit 10 extending longitudinally of the room R substantially the entire length of the latter. This conduit 10 (Figs. 3 to 6) is provided with a substantially flat horizontal upper wall 11 30 having therein a series of transverse slots preferably arranged in pairs, each pair comprising a slot 12 and a slot 13. For convenience, these slots are initially made to extend across the entire width of the conduit and 35 each slot is provided at its opposite edges with flange members 14 providing guideways for a sliding cover hereafter described. Preferably one end of each slot is provided with a fixed cover, the slot 12 having the cover 15 and the slot 13 having the cover 16, such fixed covers being secured to the flange 14. As indicated in Fig. 3 the portions of the slots 12 40 and 13 which are not covered by the members 15 and 16 respectively extend inwardly from the left-hand and right-hand sides respectively of the conduit to points adjacent to or slightly beyond the center line of the conduit.

Referring particularly to Figs. 3, 5 and 6, 45 the sliding cover for the slot 13, for example, comprises the member 17, preferably provided with the transverse bar 18 at its left-hand end, such bar having end portions which slide freely within the guideways furnished 50 by the flanges 14. The right-hand end portion of the cover member 17 is furnished with an opening for receiving the lower end of an upwardly directed nozzle 19. The cover 17 and the nozzle 19 may be made of any suitable 55 material, for example, sheet metal. Preferably, the nozzle tapers upwardly and terminates in a delivery slot 20 which is narrow in the direction of the length of the conduit but which is elongate transversely of 60 the conduit. The nozzle thus provided is in

free communication with the interior of the conduit 10, and by reason of its shape is adapted to deliver a substantially fan-shaped jet or blast of air in an upward direction.

To the right of the nozzle 19 the cover is 70 continued in the part 17^b which is secured at its left-hand edge to the nozzle and is provided at its right-hand end with a transverse bar 23 (Fig. 6) which slides in a guideway formed in extensions 14^a of the flanges 14. 75 The part 17^b is adapted to slide over a second cover element 21 having a transverse bar 24 at its left-hand edge which at times engages the bar 23, and having a second transverse bar 25 at its outer end. The member 21 in 80 turn overlies another cover member 22 having a transverse bar 26 at its inner end and a transverse bar 27 at its outer end. The several cover members 17^b, 21 and 22 are adapted, as indicated in Fig. 6, to cover the outer portion of the slot 13 when the nozzle is moved to the left from the position indicated in Fig. 5, the series of members 17^b, 21 and 22 being sufficient to cover all that portion of the slot 85 which lies to the right of the nozzle when the nozzle moves to its extreme left-hand position. In moving to the left or to the right the several transverse bars 23, 24, etc. engage each other so as to draw one after another of the cover elements laterally into operative 90 position or to cause said several cover members to collapse one upon another, as shown in Fig. 5.

The slot 12 is provided with cover elements 95 similar to those just described and is furnished with a nozzle 19^a similar to the nozzle 19.

I have here shown the side bars or rails 28 and 29 of a conventional form of tentering machine, such bars or rails being mounted 100 upon supporting guides 32 and being movable toward and from each other by means of suitable adjusting mechanism (not shown) in a manner well known in the art. Since the tentering machine per se is of usual type, I 105 have omitted to illustrate anything herein but those elements thereof necessary to show the relation of the present invention thereto. The rails 28 and 29 are furnished with guideways at their upper portions for longitudinally extending chains 30 and 31 respectively 110 provided with hooks, clamps or other usual means for engagement with the selvage edges of the web-like fabric 32. During the operation of the machine the chains 30 and 31 are 115 progressed slowly from one end of the apparatus to the other, holding the fabric 32 under tension, and as the rails 28 and 29 are adjustable toward and from each other it is 120 possible to adapt the machine for use with 125 fabrics of different widths.

The rail 29 is preferably provided at suitable intervals with depending posts 34 to which brackets 35 are attached. The inner 130 ends of brackets 35 are secured by flanges 36

or otherwise to the nozzles 19 so that the nozzles always bear a fixed relation to the rails 29 and are adjustable in and out with the latter. In the same way, the rail 28 is provided with depending posts 34 carrying brackets 35 attached by means of flanges 36 or otherwise to the nozzles 19^a etc.

Preferably I provide each main nozzle 19 and 19^a of one pair with a conduit 37 extending from one side wall of the nozzle outwardly through the rail 28 and thence upwardly to a point above the rail where it is provided with an elongate auxiliary distributing nozzle 39 or 39^a respectively provided with a narrow elongate delivery slot 40 or 40^a. The nozzles 39 and 39^a are arranged to direct the air downwardly at points closely adjacent to the chains 31 and 30 and against the upper surface of the web 32 near its selvages.

Each nozzle of the next adjacent pair of movable main nozzles, indicated for example at 19^c, is provided with a conduit 41 extending laterally and upwardly to a point just beneath the web 32 and this conduit 41 is provided with an elongate auxiliary delivery nozzle 42 adapted to deliver air against the under surface of the material near the selvage.

While as above described I have found it desirable to associate the outside auxiliary nozzles 39 and 39^a with one pair of adjustable main nozzles 19 and 19^a respectively, and to associate the inside nozzles 42 with the next pair of adjustable main nozzles 19^c, etc., I wish it to be understood that the invention is not limited to this arrangement, but that the auxiliary outside and inside nozzles may be associated in any desired sequence with the main adjustable nozzles 19, 19^a, 19^c, etc.

As shown in Figs. 3 and 5, the main nozzles 19 and 19^c are in their outermost positions, the machine being adjusted to take the widest fabric for which it is designed, but in Fig. 7 I have indicated diagrammatically the arrangement of the several nozzles when the machine is adjusted to take the narrowest fabric.

In addition to the adjustable nozzles 19 and 19^a I prefer to provide fixed nozzles 43. As here shown one such fixed nozzle is arranged between each adjacent pair of adjustable main nozzles, and preferably these fixed nozzles are disposed substantially at the center line of the conduit 10 so that they will not interfere with the other parts of the machine when it is adjusted for the narrowest fabric.

The operation of the machine is substantially as follows, it being assumed that the fabric 32 has been engaged with the hooks, clamps, or other tenter devices carried by the chains 30 and 31, and that the bars 28 and 29 have been adjusted so as to tension the fabric and stretch it to the desired degree. The chain driving means is now set into operation and the blower is started, and as the fabric

progresses from one end of the tenter frame to the other, air is delivered from the blower through the conduit 10 and through the main nozzles 19, 19^a, 19^c and 43 to the fabric. This air is preferably conditioned by passing it through the casing 4 where it may be heated if desired. This air is delivered from the nozzles 19, 43, etc. in the form of fan-shaped jets, which, collectively, form substantially a continuous blast extending from one edge to the other of the fabric. At the same time, jets of air are delivered from the auxiliary nozzles 42 directly against the marginal portions of the fabric at its under side for drying that portion of the fabric which is engaged by the clamps or hooks of the tenter chain. Likewise air is delivered from the nozzles 39 and 39^a downwardly against the upper surface of the fabric at its margins, assisting the air from the nozzles 42 in drying the selvage portions of the fabric.

Since the nozzles 19, 19^a, 19^c, etc. bear a fixed relation to the adjustable rails 28 and 29, these movable nozzles partake of the adjustment of the rails so that no matter whether the rails are occupying their extreme outermost position, or are adjusted inwardly the nozzles 19, 19^a etc. are always positioned to distribute air against the outer portions of the fabric, while the central fixed nozzles 43 furnish the necessary air for drying the mid portions of the fabric. Likewise, as the auxiliary nozzles 39, 39^a, 42 etc. move with the rails 28 and 39, they always bear a fixed relation to the selvages of the fabric and are thus adapted to furnish air for drying the selvages no matter how wide the fabric may be. Preferably the nozzles 39, 39^a, 42 etc. are elongate in the direction of length of the fabric, and if desired these nozzles may be made of such length as to provide a substantially continuous blast of air at the selvage portion of the fabric. However, such extreme elongation of the auxiliary nozzles 42 at least is seldom necessary, since the air delivered from these nozzles is confined within the angle between the fabric and the rails of the tenter frame, and thus tends to flow in opposite directions from the delivery point.

In Fig. 8 the conduit 10^x is provided with centrally disposed fixed nozzles 43^x and with laterally disposed adjustable nozzles 19^x carried by telescoping tubes 17^x which in all positions of extension or collapse communicate with the interior of the conduit 10^x.

In Fig. 9 the conduit 10^y is provided with centrally disposed fixed nozzles 43^y and the laterally disposed adjustable nozzles 19^y which are connected to the conduit by means of collapsible and expandible bellows tubes 17^y.

In Fig. 10 I have shown an arrangement in which the adjustable nozzles 19^z are secured to relatively movable conduits 10^z. These conduits may be shifted in any de-

sired manner transversely of the drying apparatus and may be connected at their ends to any suitable source of air supply.

In Fig. 11 the conduit 10^w is furnished with the centrally disposed stationary nozzles 43^w and with the laterally disposed adjustable nozzles 19^w. The nozzles 19^w are connected by swivel means to the ends of swinging tubular arms 17^w having pivotal connections with the conduit 10^w and always communicating with the interior of the latter.

In Figs. 12 and 13 I have shown a conduit 10^s provided at suitable intervals with swiveled nozzles 43^s adapted to be rotated about a vertical axis and always communicating with the interior of the conduit. These nozzles are furnished with elongate delivery slots so that by turning them they may be caused to deliver a thin sheet of air which may be disposed transversely of the width of the conduit or substantially in line with the latter.

In Fig. 14 I have illustrated an arrangement in which the conduit 10^m is disposed above the plane of the fabric 32^m held by the tenter chains 30^m and 31^m respectively. This conduit is provided with downwardly directed nozzles 43^m and laterally adjustable nozzles 19^m. It is obvious that any of the arrangements of nozzles heretofore described may be applied to a conduit disposed above the material as shown in Fig. 14 as well as to a conduit disposed below the material, and in its broader aspects I contemplate that the invention will include all such arrangements.

While I have herein illustrated certain desirable forms of apparatus, I wish it to be understood that this is merely by way of example, and that variations in size, shape, proportion and relative arrangement of parts may be made without departing from the spirit of the invention.

I claim:

1. Apparatus of the class described comprising independent nozzles for delivering a drying medium against the central portion and the opposite edge portions respectively of web-like material, each nozzle being elongate transversely of the width of the material, relatively adjustable means supporting the edge nozzles, respectively, whereby to permit said edge nozzles to be moved toward and from the central nozzle to cooperate with fabrics of different widths, and means for supplying an air current to each nozzle in all positions of adjustment thereof.

2. Apparatus of the class described having devices for engaging the opposite edges respectively of web-like material, said devices being adjustable toward and from each other, said apparatus comprising a nozzle fixed relatively to each of said devices and adjustable therewith, each nozzle being elongate transversely of the material, and means for delivering a drying air current to said nozzles.

3. Apparatus of the class described having a pair of tenter devices for engaging the opposite edges respectively of web-like material, one at least of said tenter devices being bodily adjustable in a direction toward and from the other, said apparatus comprising a nozzle fixed relatively to the bodily adjustable device and partaking of the adjustments of the latter, and means for delivering a drying air current to said nozzle in all positions thereof.

4. Apparatus of the class described having a pair of tenter devices for engaging the opposite edges respectively of web-like material, and adjustable supporting means for each tenter device arranged to permit separation or approach of the devices, said apparatus comprising a nozzle fixedly connected to each of said adjustable supporting means and movable with the latter, and means for supplying desiccating air current to each nozzle in all positions of adjustment thereof.

5. Apparatus of the class described having a pair of tenter chains for engaging the opposite edges respectively of web-like material, and means supporting said chains for bodily adjustment toward and from each other, said apparatus comprising a conduit disposed below the plane of the chains and between them, two series of sliding nozzles disposed below the plane of the chains, the nozzles of one series being fixed to and adjustable with the supporting means for one chain and the nozzles of the other series being fixed to and adjustable with the supporting means for the other chain, said nozzles communicating with the conduit in all positions of adjustment, and means supplying the conduit with air for delivery from the several nozzles.

6. Apparatus of the class described having a pair of tenter chains for engaging the opposite edges respectively of web-like material, and means supporting said chains for bodily adjustment toward and from each other, said apparatus comprising a conduit disposed below the plane of the chains and between them, two series of movable nozzles disposed below the plane of the chains, one series being adjustable with the supporting means for one chain and the other series being adjustable with the supporting means for the other chain, a series of fixed nozzles also disposed below the plane of the chains, all of the nozzles being directed upwardly and communicating at all times with the conduit, and means for supplying the conduit with air under pressure for delivery from the several nozzles.

7. Apparatus of the class described having a pair of tenter chains for engaging the opposite edges respectively of web-like material,

- and means supporting said chains for bodily adjustment toward and from each other, said apparatus comprising a conduit disposed below the plane of the chains and between them, 5 two series of movable nozzles disposed below the plane of the chains, one series being adjustable with the supporting means for one chain and the other series being adjustable with the supporting means for the other 10 chain, a series of fixed nozzles disposed substantially midway between the vertical planes of the chains, all of the nozzles being shaped to deliver transverse substantially fan-shaped blasts against the material and all 15 communicating at all times with the conduit, and means supplying the conduit with air under pressure for delivery from the several nozzles.
8. Apparatus of the class described having 20 a pair of tenter devices engageable respectively with the opposite edges of web-like material, and means supporting at least one of said tenter devices for bodily adjustment toward and from the other, said apparatus comprising an air delivery nozzle fixed relatively to said tenter device so as to be adjustable therewith, said nozzle being arranged to deliver a blast of air outwardly toward the selvage of the web-like material held by the 25 tenter devices, and means for supplying air for delivery from the nozzle.
9. Apparatus of the class described having 30 a pair of tenter devices engageable with the selvage edges respectively of web-like material and supporting such material in a substantially horizontal plane, and means supporting at least one of said tenter devices for bodily adjustment toward and from the other, said apparatus comprising a nozzle 35 fixed relatively to said adjustable tenter device, said nozzle being disposed below the plane of the tenter devices and directed upwardly and outwardly toward the selvage of the web-like material, and means supplying air under pressure for delivery by said nozzle.
10. Apparatus of the class described having 40 a pair of tenter chains for engaging the opposite edges respectively of web-like material, and means supporting said chains for bodily adjustment toward and from each other, said apparatus comprising a nozzle carried by each of said supporting means and adjustable concomitantly with the respective 45 chains, said nozzles being arranged to deliver blasts of air outwardly toward the respective chains, and means for supplying air for delivery from said nozzles.
11. Apparatus of the class described having 50 a pair of tenter chains for engaging the opposite edges respectively of web-like material, and means supporting said chains for bodily adjustment toward and from each other, said apparatus comprising a nozzle adjustable concomitantly with each chain, 55 said nozzles being elongate lengthwise of the chains and being directed toward the respective chains, and means for supplying air for delivery from said nozzles.
12. Apparatus of the class described having 60 a pair of tenter devices for engaging the opposite edges respectively of web-like material, and adjustable supporting means for each tenter device arranged to permit separation or approach of the devices, said apparatus comprising a nozzle rigidly connected to each of said adjustable supporting means and adjustable with the latter, each nozzle being narrow in the direction of the length of the conduit so as to deliver a thin blast of air, a conduit leading laterally from each nozzle, each conduit having an auxiliary nozzle directed toward the selvage of the web-like material, and means for supplying air for delivery from the several nozzles.
13. Apparatus of the class described having 65 a pair of tenter devices for engaging the opposite edges respectively of web-like material, and adjustable supporting means for each tenter device arranged to permit separation or approach of the devices, said apparatus comprising a nozzle connected to each of said adjustable supporting means and movable with the latter, each nozzle being wide transversely of the conduit and relatively narrow longitudinally of the conduit and being arranged to deliver blasts upwardly against the under surface of material supported by the tenter devices, a pipe moving with each of said nozzles, each pipe having an auxiliary nozzle directed toward the selvage of the material, and means for supplying air for delivery from the several nozzles.
14. Apparatus of the class described having 70 a pair of tenter devices for engaging the opposite edges respectively of web-like material, and adjustable supporting means for each tenter device arranged to permit separation or approach of the devices, said apparatus comprising a nozzle connected to each of said adjustable supporting means and movable with the latter, each nozzle being narrow in the direction of the length of the conduit so as to deliver a thin blast of air, a conduit leading laterally from each nozzle, each 75 conduit having an auxiliary nozzle directed toward the selvage of the web-like material, each auxiliary nozzle being elongate in the direction of length of the conduit, and means for supplying air for delivery from the several nozzles.
15. Apparatus of the class described having 80 a pair of tenter devices engageable with the selvage edges respectively of web-like material and supporting such material in a substantially horizontal plane, and means supporting at least one of said tenter devices for bodily adjustment toward and from the other, said apparatus comprising a nozzle fixed relatively to said adjustable tenter device, 85

said nozzle being disposed above the plane of the tenter devices and directed downwardly toward the selvage edge of the material, and an air supply conduit leading from below the plane of the tenter devices and laterally outward and upward to the nozzle.

16. Apparatus of the class described having a pair of tenter devices engageable with the selvage edges respectively of web-like material and supporting such material in a substantially horizontal plane, and means supporting at least one of said tenter devices for bodily adjustment toward and from the other, said apparatus comprising a nozzle fixed relatively to said adjustable tenter device, said nozzle being disposed above the plane of the tenter devices and directed downwardly toward the selvage of the web-like material, and means supplying air under pressure for delivery by said nozzle.

17. Apparatus of the class described having a pair of tenter chains for engaging the opposite edges respectively of web-like material, and means supporting said chains for bodily adjustment toward and from each other, said apparatus comprising a nozzle adjustable concomitantly with each of said chains, one nozzle being directed upwardly toward one chain and the other being directed downwardly toward the other chain, and means for supplying air for delivery from said nozzles.

18. Apparatus of the class described having a pair of tenter devices for engaging the opposite edges respectively of web-like material, and adjustable supporting means for each tenter device arranged to permit separation or approach of the devices, said apparatus comprising a nozzle connected to each of said adjustable supporting means and movable with the latter, each nozzle being constructed to deliver a fan-shaped blast upwardly against the under side of material held by the tenter devices, a pipe extending laterally from each nozzle, one pipe terminating in an auxiliary nozzle below the material, and the other pipe extending outwardly and upwardly and terminating in an auxiliary nozzle above the material, and means supplying air for delivery from the several nozzles.

19. Apparatus of the class described comprising an air conduit having a wall provided with parallel slots therein, a sliding cover for each slot, each cover supporting an air delivery nozzle communicating with the conduit in all positions of adjustment of the cover, and a tenter chain carrier rigidly united to each cover.

20. Apparatus of the class described comprising an elongate air conduit having a substantially horizontal wall provided with substantially parallel slots therein, a nozzle adjustable longitudinally of each slot and communicating with the conduit in all positions

of adjustment, and means for closing all portions of each slot which are not covered by the respective nozzles.

21. Apparatus of the class described comprising an elongate conduit having a substantially flat upper wall and a pair of slots in said upper wall extending from opposite edges respectively of the conduit toward its center, a sliding cover member for each slot, each cover supporting a nozzle which communicates at all times with the interior of the conduit, and a fixed nozzle disposed substantially midway between the sides of the conduit and also communicating with the interior of the conduit.

22. Apparatus of the class described comprising an elongate air conduit having a substantially horizontal wall provided with a series of pairs of slots therein, the slots of each pair extending from opposite edges respectively of the conduit toward its center, a sliding cover for each slot, each cover carrying a nozzle which communicates at all times with the interior of the conduit, a fixed nozzle disposed between each pair of adjustable nozzles and also communicating with the interior of the conduit, and means for supplying the conduit with air under pressure.

23. Apparatus of the class described comprising an elongate air conduit having a substantially horizontal wall provided with substantially parallel slots therein, a nozzle adjustable longitudinally of each slot and communicating with the conduit in all positions of adjustment, each nozzle having fixed thereto a pair of oppositely directed cover members, and a plurality of telescoping cover members associated with at least one of said first named cover members and cooperating therewith to close that part of the slot not occupied by the nozzle.

24. Apparatus of the class described comprising an elongate air conduit having a substantially horizontal wall provided with substantially parallel slots therein, a nozzle adjustable longitudinally of each slot and communicating with the conduit in all positions of adjustment, and telescoping cover members for closing all portions of each slot which are not covered by the respective nozzles.

25. Apparatus of the class described comprising an elongate air conduit having a substantially horizontal wall provided with substantially parallel slots therein, a nozzle adjustable longitudinally of each slot and communicating with the conduit in all positions of adjustment, and a plurality of telescoping cover members associated with each nozzle and movable with the latter to close a portion of the slot not covered by such nozzle.

Signed by me at North Adams, Massachusetts, this 27th day of January 1928.

LUCIEN BUCK.
